UNITED STATES PATENT OFFICE.

WILLY FELLER, OF ESSEN-ON-THE-RUHR, GERMANY, ASSIGNOR TO FRIED. KRUPP AKTIENGESELLSCHAFT, OF ESSEN-ON-THE-RUHR, GERMANY.

AMMUNITION-BOX WITH YIELDING BEARINGS.

1,179,417.

Specification of Letters Patent. Patented Apr. 18, 1916.

Application filed February 18, 1914. Serial No. 819,473.

To all whom it may concern:

Be it known that I, WILLY FELLER, residing at Essen-on-the-Ruhr, Germany, a subject of the Emperor of Germany, have 5 invented a certain new and useful Improvement in Ammunition-Boxes with Yielding Bearings, of which the following is a specification.

The present invention relates to ammunition boxes with a device for yieldingly supporting the ammunition and consists in providing in the box a detachable, flexible band of steel or other material with a plurality of interchangeable buffers of rubber or similar 15 material, each serving as bearing for the head of a projectile.

In the accompanying drawing is illustrated one embodiment representing an ammunition box, where—

20 Figure 1 is a section and part elevation of the ammunition box and Fig. 2 a section along line 2—2 of Fig. 1 seen from above. Fig. 3, a side view of the band E with its sides curled up for passing it through the 25 bearings b¹ c¹.

The box A has a lid a¹, which may be connected with the box by hinges and is provided on its inner side with a strip a² of leather, felt or similar material. The box 30 has cross partitions B and C with stamped cylindrical bearings b¹ and c¹ respectively for each cartridge. On the bottom a³ of the box rest disk shaped buffers D, preferably made of rubber, one buffer being provided for the 35 flat head of each projectile G. These buffers are arranged in a flexible band, preferably of steel, in such a manner, that they are held at their places in the band in consequence of their own shape only. For this purpose each 40 buffer D is provided with an annular groove d¹, the smallest diameter of which coincides with the diameter of the cut e¹ of the band E. On one side of the groove d¹—the upper side—is arranged a collar d² of such a diameter that the buffer may be pressed in (from 45 below) into the cut e¹. In this operation the collar d² is first bent back and thereupon it springs out into the position shown in the drawing. Flat headed screws F are provided for securing the ends of the band E, retained by nuts f¹ to the bottom a³ of the

box. The band E which in practice is constructed very thin can consequently be bent up trough shaped as shown in Fig. 3 in order to draw it through the bearings b¹ c¹. 55 In this manner it will be readily seen that the band E, together with the buffers D may be without difficulty removed from the ammunition box through the bearings or openings b¹ c¹ or put back in position through these 60 openings and secured by screws and nuts F f¹.

When the lid a¹ is closed, the cartridges are put in between the strip a² and the buffers D, so that they cannot be injured by shocks caused by traveling. Should one of 65 the buffers D be useless, the band E with the buffers D is taken up through the bearings c¹ b¹, after the nuts f¹ have been removed, whereupon the buffers are exchanged and the band again fastened to the bottom 70 of the box. In ammunition chests which are constructed to contain two or more rows of projectiles or rounds, the buffers belonging to each row of ammunition are arranged in a separate band. 75

I claim:

1. In an ammunition box a false wall of flexible material having a plurality of apertures, corresponding in number to the number of rounds of ammunition contained in 80 the box, a solid buffer seated in each aperture for yieldingly supporting the point of a round of ammunition.

2. In an ammunition box a band of flexible material removably secured within the 85 box, said band having a plurality of apertures, corresponding in number to the number of rounds of ammunition contained in the box, a rubber buffer seated in each aperture and forming an abutment for the point of 90 a round of ammunition, said buffers being detachable from the band.

3. In an ammunition box a band of flexible material removably secured within the box, said band having a plurality of apertures 95 providing one aperture for each ammunition round contained in the box, a solid rubber buffer seated in each aperture and forming an abutment for the point of a round of ammunition. 100

4. In an ammunition box, a band of flexible metal removably secured to the bottom

of the box, said band having a plurality of apertures corresponding in number to the number of rounds of ammunition contained in the box, a buffer seated in each aperture and forming an abutment for the point of a round of ammunition, said buffers being detachable from the band.

The foregoing specification signed at Bar-
men, Germany, this 28th day of January,
1914.

WILLY FELLER. [L.S.]
